UNITED STATES PATENT OFFICE.

JOHN P. ROLEN, OF KNOXVILLE, TENNESSEE, ASSIGNOR TO DRAPER CORPORATION,
OF HOPEDALE, MASSACHUSETTS, A CORPORATION OF MAINE.

FILLING CLAMPING AND PARTING MECHANISM FOR LOOMS.

1,341,022.

Specification of Letters Patent.

Patented May 25, 1920.

Application filed November 11, 1919. Serial No. 337,309.

To all whom it may concern:

Be it known that I, JOHN P. ROLEN, a citizen of the United States, residing at Knoxville, county of Knox, State of Tennessee, have invented an Improvement in Filling Clamping and Parting Mechanism for Looms, of which the following description, in connection with the accompanying drawing, is a specification, like characters 10 on the drawing representing like parts.

This invention relates to automatic filling replenishing looms wherein the running filling is replenished prior to complete exhaustion and wherein the old or spent filling 15 is parted between the cloth and the shuttle by parting means mounted upon the carrier such as the usual swinging shuttle feeler so as to be moved bodily rearwardly and forwardly or toward and from the lay.

20 The object of the invention is to provide an improved, simple, and effective means for operating the filling, clamping and parting means when, and only when, a fresh filling carrier is transferred from the hopper or supply to the shuttle on the lay.

The invention is an improvement upon, and is similar in its general object and purpose to that shown in, the patent to Davis No. 1,084,878 granted January 20, 1914.

30 The nature and object of the invention will appear more fully from the accompanying description and drawings and will be particularly pointed out in the claim.

The drawings illustrate the invention as 35 embodied in the well known Northrop type of automatic filling replenishing looms.

In the drawings—

Figure 1 is a transverse section of a portion 40 of the automatic filling replenishing loom with the present invention embodied therein.

Fig. 2 is a detail in front elevation of the upper portion of the carrier for the filling clamping and parting means and the parts 45 connected thereto.

The construction and operation of the automatic filling replenishing loom herein illustrated being well known and familiar to those skilled in the art, and the patent to 50 Davis above mentioned showing a construction securing the same broad result as that here secured, it will be necessary to describe in detail only those features and their op-

eration immediately concerned with the present invention.

55 The loom frame 1 supports the hopper 2 containing the supply of fresh filling carriers 3. When the running filling in the shuttle on the lay has become substantially exhausted, indication of that fact is transmitted through a well known mechanism to the rod 4 which is thereupon rocked to raise the arm 5 and swing the shuttle feeler 6 rearwardly and at the same time to raise the dog 7 connected to the transerrer 8 into the 60 path of a bunter 9 on the lay 10. If the shuttle is properly boxed allowing the shuttle feeler to pass the end of the shuttle, then the bunter 9 striking the dog 7 swings the transerrer 8 downwardly, forcing a fresh 65 filling carrier 3 from its position in the hopper down into the shuttle 11 on the lay therebeneath, and simultaneously ejects the partially spent shuttle therefrom. When the fresh filling carrier is in the hopper 70 ready for transfer it rests against an abutment 12 and over a support 13 pivoted at 14 so that in order to pass out from the hopper into the shuttle this support 13 must be 75 swung downwardly about its pivot. This support has rigidly connected with it a finger 15. A spring 16 is held between a notched or slotted lug 17 projecting from the hopper stand 2 and the head 18 of a slide rod 19 connected with the finger 15, 80 and thus acts to hold the pivoted support 13 in, and return it to, its normal position 85 as illustrated in Fig. 1.

The shuttle feeler 6 acts as a carrier for 90 the filling clamping and parting means which is shown as of similar construction to that in the patent to Davis above referred to and comprises a movable blade 20 pivoted to the shuttle feeler at 21. This blade cooperates at its rearward end with a fixed 95 blade secured to or integral with the shuttle feeler to sever the filling, and with a fixed blade 22 secured to the shuttle feeler to clamp the parted filling upon the downward movement or depression of the rearward end of the movable blade. The operation is a familiar one. Upon the call for 100 filling replenishment the shuttle feeler 6 swings rearwardly, the movable blade is swung upwardly at its rearward end and in 105 this position the filling clamping and part-

ing means pass over the filling extending from the spent shuttle to the cloth. The movable blade is then swung downwardly parting and clamping the filling and then 5 when the shuttle feeler swings forwardly the clamped end of the filling is carried forwardly so as to bring the filling into the path of the usual temple thread cutter.

The movable blade is opened when the 10 shuttle feeler swings rearwardly by a pin 23 projecting laterally therefrom coming into contact with the lower cam surface of a catch 24 pivotally mounted at 25 upon an upstanding bracket 26. This catch swings 15 freely forwardly to allow the pin to pass when the shuttle feeler swings to forward position.

The present invention is particularly concerned with the means for effecting the closing movement of the movable blade 20 in 20 such a manner that this closing movement shall not take place unless the fresh filling carrier is actually transferred from the hopper to the shuttle on the lay. It sometimes 25 happens that this transfer is not effected and if the movable blade should be actuated under these circumstances the running filling would be severed and the shuttle would then 30 make two picks without laying filling and thus produce an imperfection in the goods.

In this invention the closing operation of the movable blade 20 is effected by or through the movement of the filling carrier support 13. A bracket 27 is rigidly secured to and 35 projects upwardly from the shuttle feeler 6. This bracket is extended rearwardly parallel with the head of the shuttle feeler to form a shaft or stud 28, and on this stud is pivotally mounted or fulcrumed a lever. This lever 40 is conveniently made of a single piece of stiff wire. The central portion is wound in spiral form to form the hub 29 while one end forms an arm 30 extending laterally toward the hopper and the other end forms an arm 31 45 extending in the opposite direction. The hub 29 is held in place between a collar 32 and a washer 33 secured by a cotter pin 34 on the stud 28. The arm 31 is secured by a rigid link 35 to the pin 23. To allow the required movement this link is made of a 50 piece of stiff wire coiled at one end about

the pin 23 and at the other end coiled about and engaging a hook shaped bend in the arm 31.

The finger 15 connected with the filling 55 carrier support 13 is provided with an arm 36 secured to and projecting forwardly therefrom. The arrangement of the parts is such that when the shuttle feeler with the filling clamping and parting means is moved rearwardly into position to clamp and part the filling the arm 30 will be directly beneath the arm 36. Consequently when the trans- 60 ferrer 8 swings downwardly and a filling carrier is present beneath the transerrer the 65 filling carrier support 13 will be rocked downwardly carrying with it the arm 36 thus depressing the arm 30 raising the arm 31 and rocking the movable blade 20 to de- 70 press its rearward end to clamp and part the filling.

Thus a simple and effective means is pro- 75 vided by which the movable blade is actuated to clamp and part the filling only when an actual transfer of a fresh filling carrier 80 is made from the hopper to the shuttle.

Having thus described my invention what I claim as new and desire to secure by Letters Patent is—

An automatic filling replenishing loom 80 comprising a hopper for the fresh filling carriers, a filling carrier support movable to release a fresh filling carrier from the hopper, an arm secured to and projecting forwardly from said support, filling clamping 85 and parting means including a pivotally mounted member acting when its rearward end is depressed to clamp and part the filling, a rearwardly and forwardly movable carrier for the clamping and parting means, 90 a bracket mounted on the movable carrier, a lever pivotally mounted on the bracket and having one arm extending beneath the arm projecting from the filling carrier support 95 when the carrier is in rearward position, and a link connecting the other arm of the lever to the forward end of the pivotally mounted clamping and parting member.

In testimony whereof, I have signed my name to this specification.

JOHN P. ROLEN.
